[57] CLAIM

The ornamental design for a cup or similar article, as shown and described.

DESCRIPTION

FIG. 1 is a side elevational view of a cup or similar article showing my new design, the opposite side view being a mirror image thereof;

FIG. 2 is a front elevational view thereof;

FIG. 3 is a rear elevational view thereof;

FIG. 4 is a top plan view thereof;

FIG. 5 is a bottom plan view thereof;

FIG. 6 is a sectional view thereof taken along line 6—6 of FIG. 4; and

FIG. 7 is an enlarged fragmentary elevational view of a portion of the side thereof.
